UNITED STATES PATENT OFFICE

2,579,607

CONTINUOUS DRIER

Leo J. O'Shaughnessy, South Porcupine,
Ontario, Canada

Application March 10, 1948, Serial No. 14,050

13 Claims. (Cl. 34—33)

1

This invention relates to a method and apparatus for drying granular materials.

Hitherto materials such as crushed rock, sand or crushed ore have usually been dried in rotary driers or in driers which required the use of heavy moving mechanical parts, and a substantial proportion of the cost of drying such materials has been attributable to the power consumption necessary to drive such parts. Previously known stationary driers have been subject to a number of serious disadvantages, including a non-adaptability to continuous processing, a tendency towards caking in the product, inaccessibility of pipe joints and valves for maintenance purposes and lack of efficient heat recovery means to render the process economical.

It is the object of the present invention to provide a continuous drier for granular materials which will operate efficiently without heavy moving mechanical parts.

It is another object of the invention to provide an improved continuous method for drying such materials having a high thermal efficiency and low processing cost.

It is a further object of the invention to provide a continuous method for drying granular materials in which large lumps are continually broken down on passage through a drying chamber to produce a uniform, dry, free-flowing product.

It is a still further object of the invention to provide a continuous drier for granular materials which requires a minimum of maintenance and in which parts which require regular servicing are easily accessible and do not come in contact with materials being processed.

Various other objects and advantages of the invention will be apparent from the following detailed specification, taken in conjunction with the accompanying drawings.

In the drawings—

Figure 1 shows a partly cut-away isometric projection of a drier according to the invention illustrating the general arrangement of parts.

Figure 2 is a partly sectional side view of the same drier.

Figure 3 is a detail showing the general method of mounting the pipes and forming the chamber wall.

Figure 4 is a fragmentary detail of one element of the side wall of the drying chamber.

Figure 5 is a side view partly in section of the drier shown in Figure 1 and substantially at right angles to the view shown in Figure 2.

Figure 6 is an enlarged detail of the chute doors in the feed chute and hopper shown in Figure 5.

Figure 7 is a flow diagram indicating the path followed by the drying air in its passage through the drier.

Figure 8 is a fragmentary plan view of one form

10

of vibrating means used in connection with the screens in the drying chamber.

Figure 9 is a side view of the vibrating means shown in Figure 8 taken along the line 9—9.

Figure 10 is a fragmentary detail showing the method of mounting the rocking bars in the vibrating means.

Figure 11 is a fragmentary detail of a quick closing valve used as an alternative form of vibrating means.

Figure 12 shows diagrammatically an alternative arrangement of screens in the drying chamber.

In all of the drawings non-essential structure is either not shown or is shown diagrammatically in order to avoid confusion and preserve simplicity.

15

Referring now more specifically to the drawings, in the embodiment shown a drier according to the invention consists of a drying chamber D in which are situated a plurality of heating members 10, which are substantially horizontal and so arranged in rows as to provide a plurality of sloping passageways 11 between the rows. Positioned among the heating members 10 are one or a number of foraminous members such as screens or grids 12 which may be horizontal as shown, or in any one of a number of different arrangements depending on the results desired, as will be described later. The grids or screens 12 are accessible through suitable hatches such as those shown at 12a and 12b.

20

Feed chute 13 is positioned above the drying chamber D in position to discharge material to be dried into the chamber through the chute discharge ports 14 and 15 which are separated by the angle member 16 which has its apex in the form of a knife-edge 17 pointing upwardly to aid in breaking down large lumps of feed material.

25

The chute doors 18 and 19 are formed from sheet material with a hooked end 20 which is adapted to rest on a support member 21 as shown in Figure 6 in such a way that gravity will normally cause the doors 18 and 19 to assume a closed position, but when material passing down the chute 13 is thrown outwardly by the angle member 16, the doors will be forced to an open position as shown by the dotted lines to allow passage of the feed material. Thus the feed means are substantially airtight and there will be no substantial escape of moisture laden air via the feed chute 13.

30

Positioned below the drying chamber D is some means E for collecting and delivering the dried product. The preferred means comprise a hopper 22 which discharges through a row of exhaust ports and chute doors 23 similar in construction to those on the feed chute 13, and designed to prevent any substantial entry of air from the atmosphere directly into the drying chamber from below.

Above the drying chamber D is an air conditioning chamber F which is open to the atmosphere or other air supply through the air ports 24 and 25 positioned on either side of the drier. Inside the air conditioning chamber, which is isolated from the drying chamber by partition 26, are a series of baffles 27 designed and arranged to cause the air entering through the ports 24 and 25 to follow a tortuous path through the chamber to the chamber outlet at 28. Outside and spaced apart from the walls 32 of the chambers D and F are outer walls 32 and 33 providing an enclosed space H between the inner compartment walls and the outer walls. The enclosed space H communicates at its upper end to the air conditioning chamber F through the outlet at 28, and at its lower end with the bottom of the drying chamber D through the ports 34 and 35. Passing completely through the air conditioning chamber, through the partition 26, and a top partition 29 are a series of tubes 30 which connect the drying chamber D to an outlet manifold G which discharges into an exhaust stack 31.

Circulation of air through the drier follows the plan shown diagrammatically in Figure 7. Cold air from the atmosphere enters the air ports 24 and 25, is warmed as it passes up and around the tubes 30, which are heated by the hot exhaust gases, and then passes into the enclosed space H through the outlet 28 down through the space H into the bottom of the drying chamber D where it is heated by the heating members 10, performs its drying function and rises through tubes 30 through outlet manifold G up exhaust stack 31.

The drying chamber D may be built up in any desired manner, but a particularly simple and efficient manner which is preferred according to the invention is as follows:

The two ends 40 and 41 of the drying chamber D are framed by suitable angle supports 41a. Fitting in the angle supports 41a are removable angle irons 42 and 43 as shown in Figure 3, which have a series of elongated holes 44 at uniformly spaced apart intervals. The holes 44 are adapted to receive and hold in place the ends of a series of specially designed bars 45 which have web portions 46 with heating pipe mounting holes 47 formed therein. The heating elements or pipes 10 rest on the upper extremity of one such bar 45 and are secured in position by the web portion 46 of the next higher bar 45.

The drying chamber D is separated from the enclosed space housing the pipe fittings and connections by the bars 45 and their webs 46. The ends of the heating elements 10 may be connected in series, or parallel, or preferably a combination of series and parallel arrangements completely externally to the drying chamber D and enclosed by removable housing covers 47 and 48 which also house heating medium headers 49 and 50. The covers 47 and 48 are suitably secured at top and bottom to the frame members of the drying chamber ends 40 and 41 and at either side to the outer walls 32 and 33 of the enclosed space H. Suitable header valves 51 and 52 are supplied to control flow of a heating medium such as hot gas, hot water or steam, and accessibility is achieved through removable hatches (not shown).

The action of the drier on material being dried is as follows:

Moist granular material is fed into the feed chute 13, falls down the chute, and is divided on knife-edge 17 into two portions which force the chute doors 18 and 19 to an open position and descend into the drying chamber D. The knife-

edge 17 breaks up any large lumps of material. The material gradually descends through the heating elements where it is heated and tends to follow along the passageways 11, large lumps being continually broken down by contact with the heating elements 10, the material being heated as it descends and losing some moisture to the drying air which is rising through the drying chamber D.

The moist warm material comes substantially to rest on the first grid or screen 12, where its progress is retarded due to the binding action of its moisture content, which prevents the material from falling through the foraminations. The warm drying air passing up through the drying chamber, however, permeates the foraminations and locally dries the material causing it locally to fall away from the foraminations when the binding action of the moisture is locally reduced. The conditions of moisture content for any given size and type of material at the time of falling away are largely governed by the size of the foraminations, and the larger these are the wetter the materials which will fall away. As the material locally falls away over the whole area of the grid or screen, the bulk of the material will settle and the process repeats itself, only the material which has reached a certain state of dryness passing the grid or screen.

Subsequent screens or grids may have smaller foraminations or finer mesh to ensure a higher degree of dryness of the material as it progresses down the drying chamber.

When it is desirable to pass material through one or more of the screens or grids before it has reached a certain state of dryness vibrations are imparted to the screens or grids and the flow through the foraminations is increased.

One arrangement for imparting vibrations to the screens or grids 12 is illustrated in Figures 8, 9 and 10. In this case the screens are supported by a series of rocker bars 60 which are themselves supported on supporting members 61 which are suitably supported from the frame of the drier.

The ends of the rocker bars 60 are provided with cup-shaped portions 62 which are adapted to sit upon the ball shaped studs 63 provided on the mounting members 61. Thus the rocking bars 60 are permitted to wobble quite freely to a limited extent.

A vibrator bar 64 is connected by means of similar ball and socket means 65 to each individual rocking bar 60. The vibrator bar 64 terminates in a vibrator box shown diagrammatically at 66 which is provided either with a small electric motor having an eccentrically weighted flywheel or some other suitable vibrating means.

An alternative method of producing vibrations in the drying chamber is by means of a quick closing valve connected to the exhaust header 50 and operated intermittently to produce vibrations from the shock effect created by the sudden stopping and starting of the flow of heating medium in the pipes 10. A suitable arrangement is illustrated in Figure 11 and consists essentially of a valve seat 70 situated in the exhaust manifold G. A valve head 71 attached to a valve stem 72 is adapted to cooperate with the valve seat 70.

A cam head 73 is screwed on to the opposite end of the valve stem and secured in position by a lock nut 74. Also screwed on to the opposite end of the valve stem 72 is a guide piece 75 which is adapted to slide up and down in the guideway 76 as the valve is operated.

A compression spring 77 extends between a fixed bushing 78 and the guide piece 75 and continually urges the valve stem 72 in a downward direction. A small wheel 79, adapted to rotate in the direction of the arrow, is mounted on the shaft 80 which is housed in bearings 81 in fixed position as shown at the bottom end of the guide-ways 76 below the valve stem 72.

A series of cam shaped lugs 82 is mounted on the periphery of the wheel 79 and as the wheel turns these successively engage the cam head 73 forcing the valve stem 72 in an upward direction, unseating the valve 71, and allowing heating medium to flow through the valve. As the wheel continues to operate, however, the cam 82 suddenly disengages the cam head 73 and the spring 77 reasserts itself to seat the valve head 71. The heating medium flow is brought to a stop abruptly causing the whole drying chamber to shake. The rapid succession of similar operations as successive cam shaped lugs 82 engage the cam head produces constant vibrating throughout the chamber. Very little power expenditure is necessary to operate a vibrator of this nature and a small electric motor may be used to rotate the wheel 79.

The dry material is finally collected in the hopper 22 and discharged through the chute doors 23.

Various arrangements of screens and grids may be employed to vary the effects produced. For instance, sloping screens may be used to carry on a partial separation of particle sizes simultaneously with the drying action or combinations of sloping and horizontal screens, or curved screens may be employed to produce different results. Where the material has a tendency to cake, some such arrangement of screens as shown in Figure 12 is desirable so that the material is subjected to a continual tumbling action as it descends among the heating members 10 and partially along and partially through the sloping grids. It is a simple matter to change the arrangement of the grids or screens and a matter of mere mechanical skill to adapt the arrangement to produce the most efficient results for any given material.

Added heat economy may be provided if desired by coating the outside of the entire apparatus with asbestos insulating compound.

What I claim as my invention is:

1. A continuous drier for granular materials comprising a drying chamber, means for supplying material to be dried to said chamber, dried material collecting and delivering means below said chamber, means for providing an upward flow of pre-conditioned air through said drying chamber, a plurality of substantially horizontal substantially parallel spaced apart heating members traversing said chamber, said heating members being arranged in sloping rows to provide sloping passageways between said rows, and means for retarding the descent of all the material being dried until a certain condition of local dryness has been achieved therein comprising a foraminous sheet positioned adjacent said heating members and forming a drying boundary extending across said chamber.

2. A continuous drier for granular materials comprising a drying chamber, means for supplying material to be dried to said chamber, dried material collecting and delivering means below said chamber, means for providing an upward flow of pre-conditioned air through said drying chamber, a plurality of substantially horizontal

substantially parallel spaced apart heating members traversing said chamber, said heating members being arranged in sloping rows to provide sloping passageways between said rows, and foraminous means positioned among said heating members to retard the descent of material being dried until a certain condition of dryness of said material has been achieved, said means for providing an upward flow of pre-conditioned air through the drying chamber comprises an air-conditioning chamber positioned above said drying chamber, air intake means communicating said air-conditioning chamber to a source of air, baffle means within said air-conditioning chamber for causing air to follow a tortuous path therethrough, a plurality of tubes communicating the drying chamber to an exhaust stack arrangement above said air-conditioning chamber, said tubes passing through said air-conditioning chamber to exchange heat with air flowing therethrough, and means communicating the top of the said air-conditioning chamber to the bottom of the said drying chamber, said means including an air conducting passageway formed externally to the said drying chamber and said air-conditioning chamber.

3. A continuous drier for granular materials as defined in claim 2 in which the means communicating the top of the air-conditioning chamber to the bottom of the drying chamber consists of an air passageway formed outside and substantially surrounding both of said chambers, said passageway being defined on its inner side by the walls of the said chambers and on its outer side by an outer wall spaced apart from said walls of said chambers.

4. A continuous drier for granular materials comprising a drying chamber, means for supplying material to be dried to said chamber, dried material collecting and delivering means below said chamber, means for providing an upward flow of pre-conditioned air through said drying chamber, a plurality of substantially horizontal substantially parallel spaced apart heating members traversing said chamber, said heating members being arranged in sloping rows to provide sloping passageways between said rows, and foraminous means positioned among said heating members to retard the descent of material being dried until a certain condition of dryness of said material has been achieved, said heating members traversing the drying chamber are tubular and are mounted in sloping rows on specially designed bar members, said bar members having bar portions and web portions, the web portions being formed with a plurality of spaced apart recesses, said recesses being designed when said bar members are in position to receive and hold in position said heating members, the connections of said heating members being external to the wall formed by said bar members when in position.

5. A continuous drier for granular materials as defined in claim 1 in which the sheet comprises at least one screen having a mesh that will not pass damp granular material but will pass dry granular material, and in which said screen is at an angle to the horizontal.

6. A continuous drier for granular materials as defined in claim 1 including vibrating means to vibrate the retarding means in the drying chamber and increase flow of material therethrough.

7. A continuous drier for granular materials comprising a drying chamber, means for supply-

ing material to be dried to said chamber, dried material collecting and delivering means below said chamber, means for providing an upward flow of pre-conditioned air through said drying chamber, a plurality of substantially horizontal substantially parallel spaced apart heating members traversing said chamber, said heating members being arranged in sloping rows to provide sloping passageways between said rows, and foraminous means positioned among said heating members to retard the descent of material being dried until a certain condition of dryness of said material has been achieved, vibrating means to vibrate the retarding means in the drying chamber and increase flow and material therethrough, said vibrating means comprising a mounting for the foraminous means consisting of a plurality of rocking bars rockably mounted at either end to opposite sides of said drying chamber, a vibrator bar rockably connected to each of said rocker bars and connected at one end to vibrator means mounted on the outside of the drier.

8. A continuous drier for granular materials comprising a drying chamber, means for supplying material to be dried to said chamber, dried material collecting and delivering means below said chamber, means for providing an upward flow of pre-conditioned air through said drying chamber, a plurality of substantially horizontal substantially parallel spaced apart heating members traversing said chamber, said heating members being arranged in sloping rows to provide sloping passageways between said rows, and foraminous means positioned among said heating members to retard the descent of material being dried until a certain condition of dryness of said material has been achieved, vibrating means to vibrate the retarding means in the drying chamber and increase flow of material therethrough, said vibrating means comprising a quick closing valve mounted near the outlet header of said heating members and adapted to open and close to cause the drying chamber to be intermittently vibrated by the intermittent checking of flow of heating medium through said heating members.

9. A continuous drier for granular materials as defined in claim 8 in which the quick closing valve comprises a valve seat in the outlet header, a valve head adapted to cooperate with said valve seat, a valve stem attached to said valve head, spring means continually urging said valve to a closed position, cam means secured to the end of said valve stem and rotatable means for intermittently displacing said cam means to open said valve.

10. A continuous drier for granular materials as defined in claim 9 in which the rotatable means comprises a power driven wheel comprising at least one circumferentially mounted cam shaped lug adapted on rotation of said wheel to cooperate with the cam means secured to the valve stem to longitudinally displace the same.

11. A method of continuously drying granular materials which comprises feeding said materials into a drying chamber, heating said materials and retarding flow of said materials for foraminous means having a mesh that will not pass moist granular material but will pass dry granular material, exposing said materials to the action of an updraft of drying air, whereby said air, permeating foraminations in said foraminous means, locally dries the material in the immediate area of said foraminations causing dried material to fall away therethrough and causing the bulk of said material to shift to continually expose fresh moist material over said foraminations.

12. A method as defined in claim 11 comprising vibrating said foraminous means to increase the flow of material therethrough.

13. A method of continuously drying granular materials which comprises feeding said materials into a drying chamber, heating said materials and retarding flow of said materials by foraminous means having a mesh that will not pass moist granular material but will pass dry granular material, exposing said materials to the action of an updraft of pre-conditioned air, whereby said air, permeating foraminations in said foraminous means locally dries the material in the immediate area of said foraminations causing dried material to fall away therethrough and causing the bulk of said material to shift to continually expose fresh moist material over said foraminations, and vibrating said foraminous means by intermittently stopping and starting the flow of heat through heating members in the drying chamber.
